*Primary Examiner—Ruth McInroy**Attorney, Agent, or Firm—Harness, Dickey & Pierce*[57] **CLAIM**

The ornamental design for an vacuum cleaner nozzle, as shown and described.

DESCRIPTION

FIG. 1 is a perspective view of a vacuum cleaner nozzle showing our new design;

FIG. 2 is a top view thereof;

FIG. 3 is a right side elevational view thereof;

FIG. 4 is a front elevational view thereof;

FIG. 5 is a rear elevational view thereof;

FIG. 6 is a bottom plan view thereof; and,

FIG. 7 is a left side elevational view thereof.

FIG. 1.

FIG. 2.

FIG. 3.

Fig. 2.
